E. P. HUTTGER,
CIGAR BUNCHING AND FORMING MACHINE,
APPLICATION FILED MAR. 21, 1916.

Patented Apr. 23, 1918.

UNITED STATES PATENT OFFICE.

EDWARD P. HUTTGER, OF PHILADELPHIA, PENNSYLVANIA.

CIGAR BUNCHING AND FORMING MACHINE.

1,263,673.

Specification of Letters Patent. Patented Apr. 23, 1918.

Application filed March 21, 1916. Serial No. 35,689.

To all whom it may concern:

Be it known that I, EDWARD P. HUTTGER, a citizen of the United States, residing at Philadelphia, in the county of Philadelphia and State of Pennsylvania, have invented new and useful Improvements in Cigar Bunching and Forming Machines, of which the following is a specification.

The invention relates to tobacco and more particularly to apparatus for use in the manufacture of cigars and has for an object to provide a machine for bunching and transferring the cigar in its embryo form from the bunching table to the shaping mold.

Among other features the invention comprehends a machine generally adapted to the manufacture of cigars, particular attention being devoted to a novel form of mechanism designed for the purpose of advancing what is generally known as the bunch from a forming table to the usual mold, the bunch being in the nature of a mass of tobacco later constituting the filler, and a binder in which the filler is rolled or secured.

In the further disclosure of the invention reference is to be had to the accompanying drawings constituting a part of this specification, in which similar characters of reference denote corresponding parts in all the views and in which:—

Figure 1 is a fragmentary vertical sectional view taken through a portion of my machine showing the invention.

Fig. 2 is a horizontal sectional view taken on the line 2—2 in Fig. 1.

Fig. 3 is a perspective view of the transferring element, and

Fig. 4 is a longitudinal sectional view taken through the element,

Fig. 5 is a top plan view of the transferring element. Fig. 6 is a fragmentary perspective view of one of the side plates of the transfferer.

Referring more particularly to the views, I disclose a frame 10 having a part of a cigar forming machine, the frame supporting a suitable top or table 11, formed with a depression 12, in which the tobacco is bunched to form the filler. A rolling sheet 13 of any pliable material is suitably mounted upon the table and is manually or otherwise operated to advance the filler along the table to an opening 14 therein. At the rear end of the frame there is arranged a mold

15 which receives the filler after it has the binder applied thereto.

Coming now to the essence of my invention, it will be seen that an axle 16 is journaled in the frame 10 in a compartment 17 formed in the frame and having the opening 14 as an entrance thereto. A transferring element 18 is mounted on the axle 16 and is capable of a swinging movement in the compartment, the transferring element 18 being normally in a vertical position and adapted to be swung into a horizontal position. A series of connected links 19 have connection with the axle 16 and are suitably pivoted on the frame, said links having connection with a cam element 20 rigid on a shaft 21 journaled on the frame. This shaft it will be seen, through the medium of the cam element, frame and connected links 19, will thus impart to the transferring element the desired movement. In the present instance the driving power is applied to a shaft 22, journaled on the frame and having a crank 23 operated in a slotted lever 24 rigidly secured to the shaft 21, so that the power, as shown, is initially applied to the shaft 22 and by the structure mentioned communicated to the shaft 21.

The transferring element 18, mentioned heretofore, consists essentially of a substantially U-shaped frame 25, having a cross piece 26, the frame being rigidly secured on the axle 16 so that when the axle is actuated a swinging movement will be imparted to the transferring element to swing the same from a vertical into a horizontal position or vice versa. Mounted to swing on the frame are opposed side plates 27, carrying removable jaws 28, each side plate carrying a toothed gear element 29 with the elements of the two side plates having their teeth intermeshing, whereby movement of one side plate will result in a swinging movement of the other. Contractile springs 30 connect the side plates and normally hold them so that their jaws 28 will normally lie in closed positions. A pin 31 projects from one of the side plates and as the transferring element is swung from a horizontal into a vertical position, the pin 31 engaging a lug 32 on the frame 10, will cause the side plate having the pin thereon to swing into an open position or in other words, have its free end swing outwardly from the cross piece 26, the intermeshing gear elements 29

thus causing the other side plate to similarly swing into an open position.

A rod 33 is journaled on the frame 25 and at its outer end carries a block 34 constituting an ejector, the rod having a spring 35 associated therewith, said spring abutting against a guide bar 36 on the rod with the guide bar having its ends operating in slots 37 in the frame 25, the spring thus tending to hold the rod in a normal position, thereby holding the block 34 in a normal position with respect to the side plates and jaws, the jaws and block furthermore, forming a pocket 38. The block 34 is so arranged on the free end of the rod 33 that it can be slid laterally to the rod and removed so that a larger or smaller block can be used, if desired.

A horizontally disposed plunger 39 is mounted to slide on the frame 10 and has its forward end adapted to engage the rear end of the rod 33 when the transferring element is in a horizontal position in order that the ejector will be operated when the plunger is actuated. The plunger has a spring 40 associated therewith for returning the plunger to normal position after it has been actuated and a bell crank lever 41, mounted to swing on the frame 10 has one end in pivotal connection with the plunger and the other end pivoted to a slotted link 42, through the slot of which passes a pin 43 on a beam 44, carried on the shaft 21, the shaft being merely oscillated to impart an oscillatory movement to the beam whereby through the medium of the link 42 and bell crank lever 41, the plunger will be actuated for the purpose mentioned heretofore.

Referring now to the compartment 17 it will be seen that the entrance 14 thereto opens into the pocket 38 of the transferring element when the latter is in a vertical position and that an opening 45 in the side or front of the compartment has the pocket aligning therewith when the transferring element is in horizontal position, said opening furthermore, being in registration with one of the matrices 46 of the mold 15.

In the operation of the apparatus describe a quantity of tobacco is first collected in the receptacle or depression 12 and then by means of the rolling sheet 13 it is advanced over the table to the entrance 14 of the compartment 17. The transferring element is now vertically disposed in the compartment with the pocket opened or enlarged due to the fact that the jaws of the side plates are slightly swung apart while the transferring element is in vertical position. This permits of readily advancing the bunch or quantity of collected tobacco into the pocket and when this has been accomplished the continued operation of the apparatus through the medium of the various links and levers described, operated

upon by a suitable driving power, will cause the transferring element to swing into a horizontal position in the compartment so that the pocket will register with the opening 45 in the front of the compartment. At 70 this moment the plunger 39 is operated and in turn, actuating the rod 33 imparts movement to the block 34 so that the ejector will eject the contents of the pocket into one of the matrices of the mold. The continued 75 operation of the machine now permits the plunger 39 to return to a retracted position, and the ejector 34 being also returned to a normal position, by being released from engagement with the plunger, and by the action of its controlling spring 35.

It will thus be apparent that the apparatus described in its automatic operation, not only transfers a bunch from the table to a position adjacent the mold but in fact, 85 ejects the contents of the pocket of the transferring element into the mold when the transferring element is swung into horizontal position. Although I have shown some specific mechanism for accomplishing this 90 purpose it will be understood that I do not limit myself to the particular form of apparatus described for the purpose of bringing about the transfer of the bunch from the table to the mold and the ejection of the 95 bunch into the mold. In this connection, however, particular attention is called to the novel arrangement and construction of the side plates and jaws thereof, together with the block forming a part of the ejector and 100 which is removable from the body thereof to permit of the substitution of larger or smaller blocks as desired, the jaws being also arranged for such substitution when necessary. Still further it will be noted that 105 when the jaws are relatively opened their swinging action is precisely the same although in opposite directions and one jaw will swing outwardly a distance equal to the outward swing of the other jaw. This 110 movement is effected through the provision of the intermeshing toothed gear elements 29, carried by each of the swinging side plates 27, and this synchronous movement of the plates is an extremely important feature, inasmuch as it permits a bunch, discharged 115 from the rolling table, to accurately center itself within the jaws 28, so as to be in position to be firmly gripped by said jaws when the transfferer begins to oscillate downward.

Having described my invention, I claim

1. In a cigar bunching or forming machine, a transferring element comprising a frame, interchangeable jaws carried by the frame and formed with a bunch-receiving pocket, an ejector movably carried by the frame for discharging the contents of the pocket therefrom, resilient means tending to hold the jaws in position to grip the con- 130

tents of the pocket, and means for simultaneously moving said jaws to an open position for the reception of a cigar bunch.

2. In a cigar bunching or forming machine, the combination with a bunch-rolling mechanism and a vertically disposed bunch-receiving mold, of a transferring element for transferring the bunch from the rolling mechanism to the mold, comprising an oscillating frame, a plurality of bunch-holding jaws pivotally carried by said frame, intermeshing gear elements formed with said

jaws, and operable to oscillate the latter synchronously, removable pocket-forming plates carried by said jaws for the reception of a cigar bunch, an ejector movable between said plates for effecting the discharge of a bunch from the transerrer into said mold, and means for oscillating said transerrer from a substantially vertical bunch-receiving position to a horizontal bunch-ejecting position.

In testimony whereof I affix my signature.
EDWARD P. HUTTGER.
